UNITED STATES PATENT OFFICE.

ALBERT VEITL, OF DEADWOOD, SOUTH DAKOTA, ASSIGNOR OF ONE-THIRD TO JOHN BROSIUS, OF SHERIDAN, WYOMING.

WASHING-MACHINE.

1,174,108.

Specification of Letters Patent.

Patented Mar. 7, 1916.

Application filed January 27, 1915. Serial No. 4,744.

To all whom it may concern:

Be it known that I, ALBERT VEITL, a citizen of the United States, residing at Deadwood, in the county of Lawrence and State 5 of South Dakota, have invented certain new and useful Improvements in Washing-Machines, of which the following is a specification.

This invention relates to machines for 10 washing various materials or commodities, such as clothes, vegetables, dishes, or the like, and has for one of its objects to improve the construction and increase the efficiency and utility of devices of this character.

Another object of the invention is to provide a simply constructed device wherein the articles or materials to be washed are subjected to the action of a cleaning liquid 20 or like material under pressure and which is caused to pass rapidly and forcibly upwardly and downwardly therethrough.

With these and other objects in view the invention consists in certain novel features 25 of construction as hereinafter shown and described and then specifically pointed out in the claims; and in the drawings illustrative of the preferred embodiment of the invention, Figure 1 is a side elevation of the 30 improved device. Fig. 2 is a vertical sectional elevation on the line 2—2 of Fig. 1. Fig. 3 is a transverse sectional elevation on the line 3—3 of Fig. 1. Fig. 4 is a perspective view of the detachable dish holder portion of the improved device. Fig. 5 is a 35 detail perspective view illustrating the construction of the locking device of the lever supporting standard.

The improved device comprises a casing 40 represented as a whole at 10 of any suitable size and of any suitable material. For the purpose of illustration the casing is shown in square form and constructed of sheet metal such as galvanized iron or steel 45 and reinforced at the corners by vertical L-members 11 and reinforced at the lower side by horizontal L-members 12. The corner members 11 are preferably extended to form legs 13, flaring outwardly, and supporting the casing 10 at a suitable elevation 50 above the ground or floor. The casing

10 is provided with a draw off valve or spigot 14 to enable the cleansing liquid to be removed from the receptacle. Mounted within the receptacle 10 is a receiver for the 55 garments or other material or products to be cleansed and formed with imperforate sides 15 and a stationary foraminous bottom 16. The body of the receiver may be of any required form, but for the purpose of 60 illustration is shown in circular or cylindrical form, but it will be understood that it is not desired to limit the invention to any specific form of either the receptacle 65 10 or the receiver 15. At its lower edge 65 the member 15 is provided with an inwardly directed flange 17 to support the foraminous bottom member 16. Near its upper edge the body portion 15 of the receiver is provided with inwardly directed supports 70 18 to receive the rim portion 19 of a foraminous member 20, the latter forming the top of the receiver. At one side the member 15 is provided with an overhanging stationary lip 21 to bear over the upper 75 side of the rim member 19 at one point, and provided with a holding member 22 hinged at 23 to the wall of the receiver. By this means the foraminous top may be readily detached to enable the contents of the receiver to be inserted and removed.

Attached to the lower end of the receiver is a transverse member 24 extending at its ends beyond the receiver and engaging in sockets 25 within the receptacle. The sockets 25 are formed open at one end with the open ends extending in opposite directions, so that when the receiver is deposited in the receptacle and rotated for a limited distance, the terminals of the member 24 will 90 pass into the sockets 25 and be thereby prevented from upward movement. The member 24 is preferably secured to the flange 17 of the member 15 as represented at 26, and is therefore removable from the receptacle 95 with the receiver and foraminous terminal portions of the same. Locking rods 27 are disposed within the receiver and operate vertically through keepers 28 and are arranged to pass downwardly through apertures in the socket member 25 and lock the terminals of the member 24 in the sockets.

The rods 27 extend upwardly a sufficient distance to enable them to be actuated from the upper part of the receptacle when the latter is uncovered to release the receiver, as 5 hereinafter explained. By this arrangement the materials to be cleansed may be readily deposited within the receiver without removing the latter from the receptacle, but the receiver may be readily removed 10 from the receptacle by releasing the rods 27 and rotating the receptacle a short distance, as will be obvious.

Engaging over the receptacle is a hood member comprising vertical sides 29 and a 15 closed upper end 30, the latter preferably being conical, as shown, the hood member is of sufficient length so that when disposed within the receptacle and over the receiver with its lower edge bearing upon the projecting portions of the member 24, the conical upper end will project above the upper edge of the receptacle, as illustrated in 20 Fig. 2.

The cleansing liquid, indicated conventionally at 31 is deposited within the receptacle and the lower portion of the hood 29 remains constantly immersed in the liquid, as illustrated in Fig. 2.

The receptacle 10 is provided with a top 30 indicated as a whole at 32 and formed with a central opening through which the hood 29 operates. The member 32 is provided with a depending outer rim 33 conforming in outline to the interior of the receptacle 35 10, and an inner depending rim 34 conforming in outline to the hood 29. The opening in the member 32 and the rim 33 are somewhat larger than the hood, so that the latter will have a sufficient lateral play to prevent 40 cramping against the flange 34 by the change of center between the pivot 40 and the rod 44 when the lever 43 is actuated.

The closure 32 is slightly smaller than the interior of the receptacle 11 and is supported with its upper face below the upper line of the receptacle and supported at the corners of the receptacle by inwardly directed brackets 35, the rim portion 33 extending between the brackets, while the body 50 portion of the top 32 only rests upon the brackets. The brackets are formed with their upper faces slanting inwardly and downwardly, so that any liquid which may be splashed outwardly upon the brackets 55 will run backward into the receptacle. The upper face of the cover 32 is likewise formed to slope inwardly and downwardly from all points for the same purpose.

Means are provided in the improved device 60 for vibrating the hood member 29 vertically, and includes a standard preferably formed in two parts 36-37 spaced apart and mounted to swing at the lower ends, as illustrated at 38-39, to the receptacle 10.

At their upper ends the standards 36-37 65 are curved over the receptacle 10 and pivoted at 40 to bars 41-42, the latter bearing upon opposite sides of an operating lever 43. The bars 41-42 diverge toward one end and are pivotally engaged with a rod 44 which 70 passes through ears 45-46 rising from the conical top 30 of the hood. The rod 44 is provided at one end with an eye 47 to enable it to be readily actuated to release the members 41 and their attachments, as hereinafter 75 explained.

The members 36-37 are united by a transverse member 48 near the upper end of the receptacle. Mounted to swing at 49 to the receptacle 10 is a locking member 50, 80 preferably in the form of a loop or yoke and adapted to engage over the transverse member 48, as illustrated in Figs. 1 and 5. Attached to the receptacle 11 is a resilient catch 51 having a recess with which the lower end 85 of the member 50 engages, as illustrated in Figs. 1 and 5. By this means the member 50 is retained in yieldable relation to the transverse member 48, and thus holds the standard members 36-37 in vertical position and in yieldable locked relation to the receptacle.

Mounted for rotation in hangers 52 extending from one pair of the legs 13 of the receptacle is a shaft 53 having a crank 54 95 intermediate its ends. Pivoted at one end to the crank 54 is a connecting rod 55, the rod being pivoted at 56 at its opposite end to the members 41 and the lever arm 43. By this means it will be obvious that when the shaft 53 is rotated the crank 54 will impart a reciprocatory movement to the lever arm 43 and thus vibrate the hood 29-30 vertically. The lever arm is extended at one end into a handle, illustrated at 57, so that the 100 hood may be manually vibrated by actuating the lever arm if required.

Means are provided for rotating the shaft 53 through the medium of a chain pulley 58 on the shaft 53, a connecting chain 59 110 and a chain pulley 60 upon a counter shaft 61, the latter provided with a balance wheel 62 and a crank handle 63. At its inner end the countershaft 61 is enlarged into a head 64 which is supported between guideways 115 65. By this means the countershaft is mounted upon one of the walls of the receptacle 10, in convenient position for the operator. It will thus be obvious that when the shaft 61 is rotated by power applied to the handle 63, the motion of the countershaft will be imparted to the drive shaft 53 and thence to the members 41-42 and the hood 29. The hood is provided with a vent valve 66 to relieve the hood from pressure when 120 125 required.

Attached to the receptacle 10, preferably to an opposite pair of the corner members

11, are brackets 67 carrying a support 68 adapted to receive a wringer device, not shown. The countershaft 61 is provided with a chain pulley 69 from which a chain, 5 not shown, may be conducted to a chain pulley on the wringer. Thus means are provided for actuating the wringer from the countershaft 61 when required.

The conical top 30 of the hood is provided 10 with handles, one of which is represented at 71, to assist in handling the hood when the latter is to be detached.

With a device thus constructed the operation is as follows: The receiver 15 is preferably deposited within the receptacle 10 before the liquid 31 is inserted, but may be deposited therein after the cleansing liquid, 15 as may be preferred. The receiver is preferably locked in position by actuating the rods 27 before the contents of the receiver 20 are deposited therein. The foraminous member 20 is detached and the garments or other objects or material to be cleansed deposited within the receiver and the foraminous top replaced. The hood 29—30 is then arranged in place and the operating lever device coupled to the ears 45—46 by the pin 44. The fly wheel 62 is then actuated by power applied to the handle 63 to cause the 30 vibration of the hood 29—30. At each upward movement of the hood a partial vacuum is produced which causes the liquid to rise within the receptacle and within the hood, and above the contents of the receiver, 35 and then at each downward stroke the liquid is violently forced downwardly through the contents of the receiver and then with the next upward stroke is caused to pass upward through the contents of the receiver 40 and so on continuously, the liquid being violently forced upwardly and downwardly through the contents of the receiver and thoroughly cleansing the same. The hood may be actuated at any required speed, but 45 for ordinary purposes, the hood will be vibrated about one hundred times per minute, but the speed may be varied as circumstances or the condition or the nature of the contents of the receiver may require.

50 In Fig. 4 is shown a holder of foraminous material and represented as a whole at 72 and formed with an upwardly directed conical bottom 73 and provided with lifting handles 74. The member 72 is designed to 55 be inserted within the receptacle 15 and to be employed when the device is to be used for washing dishes and for like purposes.

The dishes and like articles are deposited within the member 72 and in turn deposited 60 within the receiver 15 and the cover 20 disposed in position or not, as may be preferred. By this means it will be obvious that the cleansing liquid may be violently forced through the dishes both downwardly

and upwardly by the movement of the 65 hood 29.

The improved device may likewise be employed for rinsing the contents of the receptacle by drawing off the cleansing liquid and substituting clean water, or other suitable liquid or compound.

The improved apparatus may also be employed for "dry cleaning" garments, as will be obvious.

Any suitable means may be employed for 75 heating the cleansing liquid, but as this forms no part of the present invention, it is not necessary to illustrate the same.

The fly wheel may be used as a belt pulley when power is to be utilized to operate 80 the device.

Having thus described the invention, what is claimed as new is:

1. In a washer, a receptacle for a cleansing liquid, a receiver for the objects to be 85 cleansed and having imperforate sides and perforated ends, said receiver being supported for movement and spaced above the bottom of the receptacle, an air-tight hood including vertical sides operating between 90 the receptacle and the receiver, and means for vertically moving said hood.

2. In a washer, a receptacle adapted to receive a cleansing liquid, a receiver adapted to hold the articles to be cleansed, 95 oppositely opening sockets within the receptacle, a locking bar carried by said receiver and projecting at the ends for detachably engaging in said sockets and maintaining said receiver from movement relative to said receptacle and spaced from the bottom of the same.

3. In a device of the class described, a receptacle, a receiver within the receptacle and spaced from its sides and bottom, the top 105 and bottom of said receiver being of perforated material normally open, a hood including imperforate sides and top with the sides of the hood operating between the receptacle and the receiver, and means for 110 vertically moving said hood.

4. In a washer, a receptacle for the cleansing liquid, a receiver for the material to be cleansed and disposed within the receptacle, said receiver including imperforate sides, a stationary foraminous bottom and a detachable foraminous top, a hood closed at the upper end and bearing over said receiver with its lower end constantly immersed in the liquid of the receiver, and 120 means for vibrating said hood.

5. In a washer, a receptacle for the cleansing liquid, a receiver for the material to be cleansed and disposed within the receptacle, a hood closed at the upper end and bearing over said receiver with its lower end located to be constantly immersed in the liquid in the receiver, a top member for the

receptacle having an opening to receive the hood and sloping inwardly toward the hood, said top being located below the upper line of the receptacle, and means for vertically moving said hood through the opening in said top member.

In testimony whereof I affix my signature in presence of two witnesses.

ALBERT VEITL. [L.S.]

Witnesses:

H. J. LINDER,
H. B. COPE.
